UNITED STATES PATENT OFFICE

EDWARD S. COLE, OF NEW YORK, N. Y.

MOUNTING FOR PITOT TUBE CONNECTIONS OR RODMETERS

Application filed June 7, 1926. Serial No. 114,355.

My invention relates to mountings for Pitot tube connections or rodmeters.

One of the objects of the invention is to provide a simple, practical and advantageous construction of mounting of the class specified.

Another object of the invention is to provide a mounting of the class specified of special strength and rigidity which will stand rough and even violent usage.

Another object of the invention is to arrange for the secure holding of the mounting in place.

Other objects of the invention are to arrange for the quick and ready adjustment of the rodmeter into and out of operative position, and to ensure the rodmeter being inserted in the proper manner.

In the accompanying drawings, Fig. 1 is a side elevation of a mounting of the class specified embodying my invention;

Fig. 2 is an end elevation of the same;

Fig. 3 is a view showing the use of this mounting in or upon a ship such as a war vessel;

Fig. 4 is a longitudinal sectional view of a casing or housing in which the mounting is arranged;

Fig. 5 is a cross section taken on line 5—5, Fig. 4.

Referring to the drawings, I show a casing conveniently comprising three members 1, 2 and 3, whereof the member 1 is to be connected to the ship side, bottom or other wall or support carrying the mounting, and whereof the members 2 and 3 are in turn connected to and supported by the member 1, the connection between these members 1, 2 and 3 being preferably by flanges 3a and 4 on member 1, and flange 5 on member 2, and flange 6 on member 3, together with connecting bolts 7—7 and 8—8.

The member 1 is shown secured to and supported by the side or bottom plate 9 of a ship or boat, although it could be otherwise mounted. The member 1 is secured by a flange 10 on said member 1 and a plate 11 on the outer side of the plate 9, together with connecting bolts 12—12, a packing 13 being

preferably used between plate 11 and supporting member 9.

The member 1 has a chamber or passage 14 registering with a corresponding passage formed in the ship wall 9 and the plate 11 so as to form an aperture or opening for the projection of a rodmeter or Pitot tube connection through the ship wall so that it may be available for obtaining velocity and static pressure as the ship travels through the water. A spigot projection 15 of member 1 is preferably fitted into the opening formed in plate 11, and ship side 9 and flange 10, and this spigot projection is preferably provided with side guideways 16 for a rodmeter such as the rodmeter 17 which is shown herein as illustrative of the principles of operation and construction of this mounting. Other types of rodmeters could of course be used. The rodmeter 17 is the subject of an application for patent executed by me of even date herewith for Pitot tube connector or rodmeter.

An aperture or opening 16 for the rodmeter is formed by members 16a, 16a preferably crescent shaped so as to form guideways for the oval shape of the rodmeter 17, and the members 16a, 16a are preferably tapered as shown in Fig. 1, and the member 15, correspondingly tapered so as to prevent said members 16a, 16a, falling out through the rodmeter orifice and becoming lost in case screw bolts 12 should become undone.

The mounting member 2 carries a gate valve 18 adapted to be projected into the interior of member 1 so that it may be operative to open and close the passage to the outside of the ship's wall through chamber 14. The gate valve 18 is carried by a rod 19 which is carried and actuated by a gear 20 in mesh with another gear 21 carried by a rotary rod 22 having a hand wheel 23 so that by turning wheel 23 the gate valve 18 may be adjusted as desired.

It will be understood that the rod 19 is mounted for rotation and stopped against longitudinal movement and the lower end thereof has screw-threaded engagement with the gate 18 so that upon rotating the rod 19 the gate will be moved up or down for opening or closing the valve. For convenience

this rod 19 is connected by the gears 20 and 21 to a hand wheel 23 on the rod 22, whereby the gate may be operated from a distance.

The mounting member 3 is more particularly adapted to serve as a holder or case for the rodmeter such as 17, and to such end is elongated and provided with an internal passage or bore 25 having a guide 26 for the rodmeter such as 17. The latter projects out the end of member 3 so that connection may be made to suitable apparatus carried by the ship or otherwise adapted for use in connection with the rodmeter.

Thus it will be seen that in using this arrangement the rodmeter may be inserted in member 3 and then gate valve 18 opened so that rodmeter 17 may be pushed on so that its orifice may be projected well into the water outside the ship, as shown in Fig. 3. In this position the rodmeter may remain as long as desired. When, however, it is desired to discontinue the use of the rodmeter or when the ship is likely to come close to or in contact with the bottom or dock the rodmeter may be withdrawn so as to prevent its becoming injured, and it will be pulled in more or less as shown in Fig. 1. At this time if desired the wheel 23 may be turned so as to lower the gate valve 18 and thereby shut off connection between the rodmeter mounting and the outside of the ship.

Thus it will be seen that the structure set forth provides a casing forming a chamber which communicates with the outside of the ship's wall or other support to which the device is attached, and also a further chamber for the rodmeter, and also a valve by which the communication between the outside opening or orifice of said chamber may be controlled so as to establish and disestablish communication between the outside orifice and the rodmeter chamber to permit the projection of the rodmeter through the ship's wall or like support for service, and the withdrawal of the same from such position, and also that the valve controlling these chambers and openings is operated from outside of the chamber and at a substantial distance from the same.

Referring more especially to Figs. 4 and 5, I show a housing 30 in which the rodmeter and its mounting above described are arranged. This housing 30 may be made of sheet metal or other suitable material and is preferably of elongated more or less tubular or cylindrical form and has its open end 31 secured to the ship side or wall 9 and its other end provided with a removable cover or manhole 32, which latter is held detachably in position by pivoted bolts 33, 33.

The housing 30 is preferably of sufficient size to completely enclose the rodmeter 17 and also to completely enclose the hand-wheel 23 and its rotary shaft or spindle 22, that is,

when said rodmeter 17 is in operative position.

As an arrangement for ensuring the insertion of the rodmeter in proper position relatively to the direction of movement of the ship, a stop 35 is provided and also a bracket 36, both mounted on the housing 30, and a clamp 37 is secured to the end of the rodmeter 17, said clamp 37 having one of its ends 37a projecting further outwardly from the side of the rodmeter than the other end so that said end 37a may not pass the stop 35, whereas the other end 37b may pass that stop 35. This permits the rodmeter to be inserted into housing 30 in such manner that the short end 37b of clamp 37 may pass stop 35 but will prevent said rodmeter from being inserted in case the rodmeter is turned backward, that is, turned 180° from the position shown in Figs. 4 and 5, so that in such position the projecting or long end 37a will engage stop 35 and prevent the further insertion of the rod meter 17. Thus, in order to permit the insertion of the rodmeter into casing 30 and into its operative position in the apparatus, said rodmeter must be turned so that short end 37b of clamp 37 is adjacent stop 35, and when in this position, the rodmeter will be properly introduced into its mounting, with the dynamic or pressure orifice facing upstream.

In order to permit the withdrawal of the rodmeter from housing 30 and its re-introduction into the same after cleaning or testing or repair, the bracket 36 is removed so as to permit withdrawal of rodmeter through the open end of housing 30, for which purpose the cover or manhole 32 is also opened. After re-introduction of the rodmeter in its proper position, bracket 36 is again secured in place and serves to hold the rodmeter against removal from the housing 30, until it is again desired to remove it for any special purpose.

It will be understood that changes and modifications may be made without departing from the spirit of the invention.

What I claim is:

1. In a device of the class specified, a rodmeter provided with holding members, a mounting therefor; said holding members and mounting being provided with cooperating inclined or tapering surfaces to prevent the outward movement of the holding members.

2. In a device of the class specified, members for holding and guiding a rodmeter and a mounting for said members, said members being substantially crescent shaped and the mounting therefor and the outer cooperating surface of the holding members being correspondingly inclined or tapered to prevent the outward movement of the holding members.

3. The combination of an outer housing containing a rodmeter and mounting there-

for, and means on the housing and rodmeter for ensuring the insertion of the rodmeter in proper position and preventing its withdrawal after insertion, said means comprising a stop and a bracket on the housing and an elongated clamp on the rodmeter, the clamp having one end of less extent than the other end whereby the first mentioned end is adapted to pass the stop and the other end is adapted to engage the stop if the rodmeter is turned to permit it and the bracket being adapted to engage the longer end of the clamp when the shorter passes the stop.

4. In a device of the class specified, the combination with a housing, a rodmeter and mounting therefor enclosed in said housing, of a member carried by the rodmeter and having side projections on opposite sides of the rodmeter, one of said projections being longer than the other; a stop secured in said housing cooperating with the said projection-bearing member, said stop permitting the passage of the shorter projection but preventing the passage of the longer projection; the said stop and the said projections arranged to prevent the introduction of the rodmeter in any but the predetermined position.

5. In a device of the class specified, the combination with a housing, a rodmeter and mounting therefor enclosed in said housing, of a stop on the said housing and a clamp carried by the rodmeter and having a projection on one side thereof of such length that it will engage said stop and having a projection on the other side thereof of such length that it will pass the said stop, the said projections and the said stop thus co-operating to permit the rodmeter to be inserted in the proper position and to prevent its insertion in an improper position.

6. In a device of the class specified, the combination of an outer housing having one of its ends provided with an opening having a removable closure, a rodmeter and a mounting, said rodmeter and said mounting arranged within the said housing, a clamp member secured to the rodmeter, unequally extending projections on said clamp member, a stop mounted within the housing, said projections and said stop cooperating to determine the positioning of the rodmeter.

7. In a device of the class described, the combination of a rodmeter, a housing therefor, a mounting for said rodmeter enclosed in said housing, means secured to said rodmeter having arms extending sideways therefrom in opposite directions, one of said arms being shorter than the other, and a stop member secured to said housing and cooperating with the arms of said means to permit movement of said rodmeter when said short arm is aligned with said stop, and prevent movement thereof when the other arm is aligned with said stop.

8. The combination of a rodmeter, a housing, a mounting for said rodmeter in said housing, said housing having an opening thru which said rodmeter may be inserted, and means for permitting the insertion of said rodmeter in a proper position and for preventing its insertion in an improper position, said means comprising a stop element secured to said housing and a clamp member secured to said rodmeter, said clamp member having a plurality of projections of unequal length, one of which is adapted to abut against said stop element to prevent an improper insertion of said rodmeter.

9. The combination of a rodmeter, a housing, a mounting for said rodmeter in said housing, and cooperating means on said housing and said rodmeter for insuring the insertion of the rodmeter in proper position and preventing its withdrawal after insertion, said means comprising a stop member and a bracket on said housing, an elongated clamp on said rodmeter, said clamp having one end adapted to pass said stop and the other end adapted to engage the stop to be stopped when the rodmeter is inserted in an improper position, said bracket being adapted to engage said clamp member on said rodmeter when said rodmeter is inserted in a proper position, said bracket being removable to permit the withdrawal of the rodmeter.

10. The combination of a cylindrical housing, a mounting means therein, a rodmeter removably mounted in said mounting means, a valve associated with said mounting means and adapted to close the same when the rodmeter is withdrawn, remotely positioned means for operating said valve, said means including a hand-wheel, means including a pair of gears for transmitting motion to said valve, said housing having an open end for inserting said rodmeter and the mounting means therefor, and a cover for closing the open end.

In witness whereof, I hereunto subscribe my name this 1st day of May, A. D., 1926.

EDWARD S. COLE.
